Patented Aug. 2, 1921.

UNITED STATES PATENT OFFICE.

JONATHAN P. ABBOTT, OF PAINESVILLE, OHIO.

EAVES-TROUGH HANGER.

1,385,978.

Specification of Letters Patent. Patented Aug. 2, 1921.

Application filed June 29, 1920. Serial No. 392,617.

To all whom it may concern:

Be it known that JONATHAN P. ABBOTT, citizen of the United States, residing at Painesville, in the county of Lake and State 5 of Ohio, has invented certain new and useful Improvements in Eaves-Trough Hangers, of which the following is a specification.

The invention herein and as represented 10 in the accompanying drawings consists in an improvement in eaves trough hangers of which Figure 1 is a side elevation complete and ready for sale, and Fig. 2 is a bottom or inside view thereof and as otherwise shown 15 in Fig. 1. Fig. 3 is an enlarged cross section of the hanger shown as bent or fashioned to suspend an eaves trough therein. Fig. 4 is a cross section on line 4—4, Fig. 3. Fig. 5 is a perspective view of a preferred 20 form or style of reinforcing piece in the hanger, and Fig. 6 is a modification of said reinforcing piece or strip.

The hanger as thus shown is made exclusively of sheet metal both for economy in 25 manufacture and sale and convenience in use, and in order that it may have the requisite strength to bear the weight of the trough with its possible accumulations of 30 snow and ice and where the hanger is supported from the roof, various expedients have been tried from time to time for such 35 reinforcement, but the present medium is deemed of surpassing adaptation and value for the reason that it supplies the maximum 40 strength directly for the hanger and also serves as a lateral brace and support for the sides thereof, thereby overcoming any possible tendency in the hanger to buckle or bend under strain.

Referring to the drawings, the hanger proper as a complete and unitary article comprises, first, the member indicated by *h* and featured by the extended tapered tongue 2 adapted to be bent into bow shape from 45 the loop or bend 3 and engaged at its extremity in the slot 4 in the larger end 5, which is bent transversely inward in approximately U-shape and has said slot 4 in its top. The said tongue or extension 2 finally is bent at its end to make hook engagement in this slot and support the trough, 50 not shown.

Intermediate of the two bends 3 and 5 at the respective end portions of the body of 55 part *h* the sides of the said body have these distinguishing peculiarities, being tapered

longitudinally from the end 5 to the bend 3 and providing flanges 7 which flare uniformly outward their entire length and are of uniform depth from end to end. The 60 back of the body *h* is somewhat rounded transversely from side to side and this with the flanges of course makes considerably for its strength under a load or strain on the trough. However, such strength is not 65 alone found sufficient, and hence I have conceived the reinforcing or strengthening member or part *d*, shown in cross section Fig. 4 and detail Fig. 5. This part or portion of the hanger is about two thirds the 70 length of the body thereof and has the longitudinal taper of said body above described and laterally flaring side flanges 8 lying flat against the flanges 7 on their inside but relatively of about twice the depth thereof 75 their entire length. This doubles the side flange strength of the hanger, lengthwise as far as need be, to sustain the hanger under any occasion of abnormal strain. The side 80 support which the flanges afford each other and the strip *d* which are held laterally in bracing and sustaining relations is especially advantageous and desirable. Finally, the said reinforcing strip or piece *d* is united with the body of the hanger as a fixed portion 85 thereof by a rivet 10 permanently engaging said parts together with the roof strap or strip *c* which has right angled end 12 with a hole therein and secured by said rivet through said hole. This completes the 90 structure as an article of manufacture and use, and the hanger goes to the trade and is handled with the portions thereof folded as seen in Figs. 1 and 2.

In Fig. 6 I show a reinforcing piece *d'* 95 which is similar in construction and function to strip *d* excepting that it has a single side flange 8.

What I claim is:

1. An eaves trough hanger having a 100 straight tapered body portion with inwardly extending flanges flared outwardly, a reinforcing piece fitted snugly inside between said flanges against the back thereof and flanged at its side to a greater depth than 105 the flanges on said body and riveted thereto at its middle portion.

2. An eaves trough hanger comprising a body having inwardly extending flanges along its sides flared outwardly, a reinforcing piece having side flanges of greater 110 depth than the flanges on said body and

lying flat against the same their entire length, a roof strap and a rivet engaged through the said reinforcing piece and said strap and body and securing the same rigidly together.

3. An eaves trough hanger constructed of sheet metal and comprising a straight body portion tapered between its ends and provided with laterally flaring flanges along 10 each side, and a sheet metal reinforcing

piece fitting between said flanges and having side flanges its entire length of greater depth than the flanges on said body and lying flat against the same at its sides and back.

Signed at Painesville, in the county of Lake, and State of Ohio, this 27th day of October, 1919.

JONATHAN P. ABBOTT.
